UNITED STATES PATENT OFFICE.

ALBERT J. PERKS, OF SPRINGFIELD, OHIO, ASSIGNOR TO WEBSTER AND PERKS TOOL COMPANY, OF SPRINGFIELD, OHIO, A COPARTNERSHIP.

PAPER-TRIMMER.

No. 817,371.

Specification of Letters Patent.

Patented April 10, 1908.

Application filed December 21, 1905. Serial No. 292,696.

To all whom it may concern:

Be it known that I, ALBERT J. PERKS, a citizen of the United States, residing at Springfield, in the county of Clark and State of Ohio, have invented certain new and useful Improvements in Paper-Trimmers, of which the following is a specification, reference being had therein to the accompanying drawings.

This invention relates to paper-trimmers, and has for its object to provide a simple and efficient device whereby the edges of wallpaper may be readily and accurately trimmed.

The invention relates to that type of trimmer in which a straight-edge is employed having a guideway which serves to guide the travel of the trimmer proper, which is slidably mounted on the straight-edge, said trimmer proper being provided with a gage portion which cooperates with the guide portion of the straight-edge.

My present invention is in the nature of an improvement upon what is set forth in Letters Patent Nos. 745,515, 745,516, and 745,517, granted December 1, 1903, to Webster and Perks Tool Company, assignee of the present invention, the first of said patents upon an application filed by me, and the two others upon applications filed by George W. Perks.

The more immediate objects of my invention are to provide a construction which will do away with any rocking motion of the trimmer-head and gage relatively to the straight-edge and its guide, rendering their relations fixed except for the longitudinal sliding hereinbefore referred to, while provision is made for positively raising and lowering the rotary cutter relatively to the head in which it is mounted, the means provided being of a character such as to enable the operator to exert a largely-increased pressure upon the rotary cutter.

A further object is to provide a trimmer which shall be readily reversible as to its direction of travel, said reversal being accomplished without requiring the removal of the trimmer from the straight-edge.

To the above ends my present invention consists in certain novel features which I will now proceed to describe, and will then particularly point out in the claims.

In the accompanying drawings, Figure 1 is a plan view of a structure embodying my in-

vention in one form. Fig. 2 is a side elevation of the same. Fig. 3 is a detail sectional view taken on the line $x-x$ of Fig. 1 and looking in the direction of the arrows. Fig. 4 is a detail sectional view taken on the line $y-y$ of Fig. 1 and looking in the direction of the arrows, the same being on an enlarged scale. Fig. 5 is a detail sectional view, on an enlarged scale, taken on the line $z-z$ of Fig. 1 and looking in the direction of the arrows; and Fig. 6 is a detail longitudinal sectional view through the cutter-regulating shaft and the connections between it and the arbor of the cutter.

In the said drawings, 1 indicates a straight-edge constructed, preferably, in substantially the same manner as the straight-edge illustrated in prior Letters Patent, Nos. 745,516 and 745,517, hereinbefore referred to, the same having a groove 2 and a metal guide-stop or corner-piece 3, which forms a wearing and guiding surface, the same projecting over the groove, as indicated at 4. This straight-edge may, however, be constructed as set forth in prior Letters Patent, No. 745,515, or in any other suitable manner which will adapt it to receive the gage hereinafter described.

The trimmer comprises a head 5, forming a housing or body portion having in its inner face a recess 6 to receive the rotary cutter. At each end of this housing there is located a gage portion 7, the two being similar in construction and one of them being shown in sectional detail in Fig. 4. Each gage portion comprises a body portion 8, adapted to rest and fit upon the upper surface of the horizontal portion of the metallic corner-piece 3, and a downwardly-depending flange 9 at its front end adapted to fit against the front surface of the vertical portion of said metallic corner-piece. Each gage portion 7 is further provided with a guide or housing 10, having an aperture 11, in which fits and slides the shank 12 of a friction guide-block 13. The housing 10 is slotted longitudinally, as indicated at 14, to receive the body of the guide-block 13 and keep the same from turning relatively to the gage. The guide-block is provided with a horizontal slot 15 to receive the overhanging edge 4 of the metallic piece 3, which fits therein and on which the guide-block slides,

said guide-block extending down into the groove 2, which accommodates it. The

outer end of the shank 12 is threaded, as indicated at 16, and receives an adjusting-nut 17, mounted thereon.

18 indicates a spiral spring coiled on the 5 projecting extremity of the shank 12 and bearing at one end against the front or outer end of the housing 10, while its other end bears against the inner face of the nut 17, the same being preferably recessed, as indicated 10 at 19, to receive and protect the outer end of the spring.

It will be seen that by the employment in connection with the body of the trimmer of two gage portions located at the opposite 15 ends thereof, and therefore separated somewhat widely, the said trimmer-body is given an extended support or bearing upon the gage, while the spring-actuated friction guide-blocks serve to hold the body steady with respect to the guide portion of the straight-edge, not only preventing all looseness and rattling, but also serving to hold the trimmer in position at any portion of the straight-edge to which it may be moved. This is 20 advantageous for the reason that it prevents the trimmer from sliding along and dropping off from the end of the straight-edge in case the latter is held or placed in a position other than horizontal, and the operator is thus 25 given greater freedom in the handling of the straight-edge.

It will be understood, of course, that the springs 18 hold the friction guide-blocks 13 in contact with the rear edge of the part 4 of the 30 metallic guide-strip and the flanges 9 against the outer face of the vertical part of said strip, which constitute lateral bearing-surfaces therefor, thus producing the desired frictional engagement of the gage portions 35 with said strip. It will also be understood that the frictional engagement and wear may be readily regulated and taken up by adjusting the nuts 17.

The trimmer is applied to the straight-edge at the end thereof, and the engagement of the gage portions therewith may be readily effected by pressing back upon the nuts 17 or on the outer ends of the shanks 12, so as to force the guide-blocks 13 far enough back 40 to permit their engagement with the guide-strip. The body of the trimmer, thus supported in a fixed angular relation to the straight-edge, carries a rotary cutter 20, mounted to rotate freely on an arbor 21, preferably in the form of a screw-bolt. This arbor 21 is secured eccentrically in a rotatory member or shaft 22, mounted to rock or rotate in a bearing 23, formed in the body 5 of the trimmer and extending outward therefrom in a sleeve-like form. The connection 45 between the arbor 21 of the rotary cutter and the shaft 22 may be of any suitable character; but I prefer the construction shown, which is illustrated in detail in Fig. 6. In 50 this construction the shaft 22 has formed en-

tirely through it longitudinally an eccentric aperture 24, threaded internally, into which the screw 21, which constitutes the arbor of the cutter 20, screws at one end. A screw 25, screwing into the aperture 22 from the opposite end, forms a stop to limit the extent of entrance of the screw 21 into said aperture and prevents the same from loosening or being turned home so tightly as to bind and prevent rotation of the cutter 20.

The shaft 22 by its rotation controls the position of the cutter by shifting its axis of revolution upward and downward, owing to the eccentricity of said axis relatively to the axis of the shaft 22. To rock or rotate the 70 shaft 22, and thus cause the cutter to be projected more or less below the bottom of the straight-edge or withdrawn above the plane of the same, the shaft 22 is provided with a handle 26, which may be secured thereon in 80 any suitable manner. The construction I prefer, however, for this connection is that shown in which the handle terminates in a sleeve or hub 27, through which passes a set-screw 28, threaded into an aperture 29 in the hub and extending inward beyond the same. The shaft 22 is provided with a plurality of notches or recesses 30, arranged circumferentially around the exterior of the same in alignment with the end of the set-screw 28, which 85 may thus be engaged with any desired one of said notches. By this means the angular relation of the handle 26 to the eccentricity of the axis of the cutter may be adjusted in such a way that the cutter may be caused to project downward below the straight-edge to a greater or less extent for any given angular position of the handle to the vertical or horizontal. It will be noted, however, that when the line connecting the centers of the shaft 22, and arbor 21 and the central line of the handle lie in the same plane, as shown in Fig. 2, a movement of the handle downward in either direction from the vertical position shown in full lines in said figure will cause the cutter to project into operative position below the straight-edge, as indicated in dotted lines in 90 said figure. By reason of this construction the trimmer is practically reversible and may be operated in either direction with the handle toward the operator or may be used either 95 right or left handed.

In practice the operator grasps the handle 26 and by its means not only depresses the cutter to sever the paper, but also propels the trimmer along the straight-edge. It will be at once seen that the arrangement and construction are such as to give a good leverage and enable the operator to exert a heavy pressure upon the rotary cutter, thereby insuring its efficiency as a cutting implement.

I do not wish to be understood as limiting myself to the precise details of construction hereinbefore described, and shown in the accompanying drawings, as it is obvious that 130

these details may be modified without departing from the principle of my invention.

Having thus fully described my invention, what I claim as new, and desire to secure by Letters Patent, is—

- 5 1. A straight-edge having a guiding portion, in combination with a trimmer provided with a cutter and having a gage portion fitting the guiding portion and constructed and arranged to grip the same laterally with a yielding frictional pressure, substantially as described.
- 10 2. A straight-edge having a guiding portion provided with opposite lateral bearing-surfaces, in combination with a trimmer comprising a head having a cutter, and a gage portion fitting the guiding portion of the straight-edge, said gage portion comprising a spring-actuated friction member bearing against one of the lateral bearing-surfaces of said guide portion, substantially as described.
- 15 3. A straight-edge having a guiding portion provided with opposite lateral bearing-surfaces, in combination with a trimmer comprising a head having a cutter, said trimmer having gage portions at its opposite ends fitting the guiding portion of the straight-edge, each gage portion comprising a spring-actuated friction member bearing against one of the lateral bearing-surfaces of said guide portion, substantially as described.
- 20 4. A straight-edge having a guiding portion provided with opposite lateral bearing-surfaces, a top bearing-surface, and a contact-surface oppositely disposed, in combination with a trimmer comprising a head having a cutter, and a gage portion supported on the top bearing-surface of the guiding portion of the straight-edge and having members which bear against the lateral bearing-surfaces thereof, one of said members being spring-actuated to cause it to bear against its co-operating bearing-surface with a yielding frictional pressure, said gage portion engaging the under surface of the guiding portion, substantially as described.
- 25 5. A straight-edge having a guiding portion provided with opposite lateral bearing-surfaces, a top bearing-surface, and a contact-surface oppositely disposed, in combination with a trimmer comprising a head having a cutter, and a gage portion supported on the top bearing-surface of the guiding portion of the straight-edge and having members which bear against the lateral bearing-surfaces thereof, one of said members being spring-actuated to cause it to bear against its co-operating bearing-surface with a yielding frictional pressure, said spring-actuated member engaging under the downwardly-disposed contact-surface of the guide, substantially as described.
- 30 6. A straight-edge having a metallic guide comprising a vertical and a horizontal mem- ber, the latter having a free marginal portion, in combination with a trimmer having a head having a cutter, and a gage portion adapted to fit against the outer face of the vertical portion of the guide and the upper face of the horizontal portion thereof, said gage portion comprising a spring-actuated member extending around the free margin of the horizontal portion of the guide and bearing against the edge thereof, substantially as described.
- 35 7. A straight-edge having a guiding portion, in combination with a trimmer provided with a cutter and having a gage portion fitting the guiding portion and constructed and arranged to grip the same laterally with a yielding frictional pressure, said gage portion being provided with means for regulating the frictional pressure, substantially as described.
- 40 8. A straight-edge having a guiding portion provided with a free lateral margin, in combination with a trimmer comprising a head having a cutter, and gage portions located at the ends of said head and adapted to bear against the top and outer faces of the guide, each gage portion having mounted to slide therein a friction guide-block slotted to receive the free margin of the guide, each block having a projecting threaded stem, an adjusting-nut thereon, and a spring thereon controlled by the adjusting-nut, substantially as described.
- 45 9. A straight-edge having a guiding portion, in combination with a trimmer comprising a head mounted to slide thereon and having otherwise fixed relations thereto, said head having a rotary cutter, an actuating-handle for the head movable relatively thereto about the center of the cutter, and means whereby said cutter is depressed and raised in unison with said handle, substantially as described.
- 50 10. A straight-edge having a guide, in combination with a trimmer comprising a head fitted to slide longitudinally on said guide, a rotatory member mounted in said head and provided with a handle, and a rotary cutter carried by said rotatory member and having its axis eccentrically arranged relatively thereto, substantially as described.
- 55 11. A straight-edge having a guide, in combination with a trimmer comprising a head fitted to slide longitudinally on said guide, a rotatory member mounted in said head and provided with a handle, and a rotary cutter carried by said rotatory member and having its axis eccentrically arranged relatively thereto, the connection between said rotatory member and handle being adjustable to vary the angular relation between said handle and the eccentricity of the cutter-axis, substantially as described.
- 60 12. A straight-edge provided with a guide, in combination with a trimmer comprising a

body fitted to slide thereon and having a bearing-sleeve, a shaft mounted in said bearing-sleeve, a handle for operating said shaft, an arbor eccentrically mounted in said shaft, and a rotary cutter mounted on said arbor, substantially as described.

13. A straight-edge provided with a guide, in combination with a trimmer comprising a body fitted to slide thereon and having a bearing-sleeve, a shaft mounted in said bearing-sleeve, a handle for operating said shaft, an arbor eccentrically mounted in said shaft, and a rotary cutter mounted on said arbor, said body constituting a housing for said cutter, substantially as described.

14. In a paper-trimmer, a body comprising a housing having a bearing-sleeve, a shaft mounted in said sleeve and projecting beyond the same at each end, a rotary cutter eccentrically mounted on one end of said shaft, and a handle mounted on the other end of said shaft and adjustable to different angular po-

sitions relatively thereto, substantially as described.

15. The combination, with a straight-edge 25 having a guide with bearing or contact surfaces on four sides thereof, of a trimmer comprising gage portions adapted to contact with the four sides of the guide and bearing frictionally with a yielding contact on the lateral 30 portions thereof, and a head rigidly connected with said gage portions and comprising a housing and bearing, a shaft mounted in said bearing, a rotary cutter eccentrically supported by said shaft, and an operating-handle secured to said shaft, substantially as described.

In testimony whereof I affix my signature in presence of two witnesses.

ALBERT J. PERKS.
